CLAIM

The ornamental design for a display attachment for a modular dictation unit or the like, as shown and described.

DESCRIPTION

FIG. 1 is a perspective view of a display attachment for a modular dictation unit or the like showing our new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a left side elevational view, the right side being a mirror image thereof.

FIG. 1.FIG. 2.FIG. 3.

FIG. 4.

FIG. 6.

FIG. 5.
